GEORGE A. COPELAND, OF ROCHESTER, NEW YORK

PACKING CASE

Application filed October 2, 1930. Serial No. 485,859.

My present invention relates to receptacles and more particularly to packing cases adapted for the shipment of more or less fragile goods, and it has for its object to provide a case of this nature that can be constructed at low cost; which can be easily assembled; and which will so support the article being shipped that it will not come into harsh contact with any solid surface but will be hung in the container in such a way that it will be cushioned in all directions.

To these and other ends, the invention resides in certain improvements and combinations of parts, all as will be hereinafter more fully described, the novel features being pointed out in the claims at the end of the specification.

In the drawings:

Fig. 1 is a plan view of the interior of the container showing the cushioning devices and the contained article, the surrounding container or box being shown in horizontal section in a plane just below the top wall thereof;

Fig. 2 is a side view of the said interior parts, the outer container being shown in section in a plane coincident with the inner surface of a side wall thereof;

Fig. 3 is a perspective view of one of the cushioning devices, and

Fig. 4 is a plan view of the blank from which the cushioning device of Fig. 3 is formed.

Similar reference numerals throughout the several views indicate the same parts.

The precise construction of the container or box is not important to the features of the invention and is shown herein as consisting merely of an ordinary heavy paper carton 1 having side walls formed in one piece with the ends joined at one corner by an adhesive tape 2. The top and bottom of the container is formed by overlying inner and outer flaps 3 and 4 extending from the side walls and pasted or otherwise secured in place to seal the container.

The enclosed article, that is packed for shipping in accordance with my invention, is indicated at A and may consist of the bare article itself or an inner box containing it.

It is held in the center of the outer container 1 and spaced all around from contact with the walls thereof by the cushioning devices, indicated generally at C, which are of the form shown in Fig. 3 and are bent up from the blank shown in Fig. 4 and scored along the lines indicated in that figure. Referring more particularly to Figs. 1 and 3, the bending of the blank produces the following formation: The ends 6 and 7 are brought together at an angle of ninety degrees to fit the corner of the container 1; the central portion is bent in a similar right angle with its sides parallel to the previously mentioned angle along the central scored line 5 to receive a corner of the contained article A in the manner shown in Fig. 1; the portions intermediate this central portion 5 and the said end portions 6 and 7 are folded on the lines 5^a and 5^b to form reentrant angular portions 8 and 9 that lie between the walls of the angular portion 5 and the angularly disposed end portions 6 and 7 in the corner of the container.

The result is that the contained article A has a floating support cushioned against the strain of its weight in all directions. If this strain is cornerwise or at the resultant angle of forty-five degrees toward the corner of the box, it is jointly supported by both cushions 8 and 9. If such strain or weight is exerted toward either adjoining wall of the box, it is cushioned directly by the resiliency of the angle portion 8, for instance, while at the same time its movement in that direction is resisted by a longitudinal strain upon the walls of the angle portion 9 as well as the parallel walls of the angle portion 5 and the end portion 6. In other words, when one of the folded portions 8 or 9 is under lateral cushioning compression, the other folded portion acts as a hanger to resist movement of the enclosed article substantially endwise of the planes of its folds.

As shown, each corner cushioning device is the same and the above description in the singular applies to them all. Regardless of the weight of the enclosed article A it will be seen that it is practically impossible

to collapse any cushioning element entirely.

I claim as my invention:

1. In a shipping box or the like, the combination with a rectangular outer container, of a shock absorbing device fitted into the corner thereof and composed of resilient sheet material having a central reentrant angular portion adapted to form a seat for a corner of the enclosed article, and a folded angular portion constituting a cushion disposed between each wall of said central angular portion and the opposite parallel wall of the container, such cushion comprising a reentrant fold in the material connected 10 by a fold to the said wall of the central portion and by a fold to a portion of the sheet disposed against such opposite parallel wall of the container.
2. In a shipping box or the like, the combination with a rectangular outer container, 20 of a cushioning device fitted into the corner thereof and composed of an integral piece of resilient sheet material having a central reentrant angular portion adapted to form 26 a seat for a corner of the enclosed article, and a reentrant folded angular portion disposed between each wall of said central angular portion and the opposite parallel wall of the container, the ends of the sheet 30 being brought together in abutting relationship in the said corner of the container.

GEORGE A. COPELAND.
